UNITED STATES PATENT OFFICE.

ALFRED G. F. KUROWSKI, OF BROOKLYN, NEW YORK, ASSIGNOR TO UNDERWOOD TYPEWRITER COMPANY, OF NEW YORK, N. Y., A CORPORATION OF DELAWARE.

TYPEWRITING MACHINE.

1,425,024.

Specification of Letters Patent.

Patented Aug. 8, 1922.

Application filed August 5, 1919. Serial No. 315,372.

To all whom it may concern:

Be it known that I, ALFRED G. F. KUROWSKI, a citizen of the United States, formerly a citizen of Germany, residing in Brooklyn 5 Borough, in the county of Kings, city and State of New York, have invented certain new and useful Improvements in Typewriting Machines, of which the following is a specification.

10 This invention relates to typewriting machines in which type-bars are mounted in an arc on a segment and adapted to swing radially to a common point, to print against the front side of a platen.

15 The invention relates more particularly to means to support the segment upon which the type-bars are mounted.

20 A feature of the invention is to arrange a bridge or cross-bar to support the type-bar segment in front thereof, thereby securing room at the rear of the segment for the feed-rolls that run on the platen, and for other carriage parts.

25 In carrying out the invention, I have found it advantageous to provide the cross-bar with an arcuate portion or depression to fit into an arcuate groove formed in the type-bar segment, thereby avoiding other parts on the type-bar segment and reducing 30 bulk to a minimum.

35 It has been proposed to mount the type-bar segment on the bridge or cross-bar which is integral with the main frame of the machine. I have found it advantageous, however, to provide a separate cross-bar which may be assembled with the type-bar segment to form a unit, to be placed in the machine after assembling.

40 One advantage in making the cross-bar and type-bar segment of separate parts is to facilitate the machining of the type-bar segment and especially the cutting of the slots therein.

45 Another advantage of this structure is that type-bar segments with a greater or less number of type-bars may be assembled with the cross-bars.

Other features and advantages will hereinafter appear.

50 In the accompanying drawings,

Figure 1 is a sectional side view of an Underwood machine, showing my invention applied thereto; the section being taken near the middle of the machine.

Figure 2 is a perspective view of the type-bar segment and the cross-bar assembled. 55

Figure 3 is a perspective view of the type-bar segment and the cross-bar, before assembling.

Figure 4 is a detail perspective view of 60 one end of the type-bar segment as seen from the back, together with a portion of the segment-supporting cross-bar.

Key-levers 10, when depressed by keys 11, swing bell-cranks 12 about their fulcrum 13 65 to swing type-bars 14 upwardly and rearwardly to cause types 15 to print against the front side of a rotatable platen 16 on a traveling carriage 17.

The type-bars 14 are adapted to swing 70 about a curved pivot rod 18 held in a groove 20 formed in the back of a type-bar segment 21 which may be provided with radial slots 22, to guide the type-bars towards a common printing point. 75

The type-bars 14 at the end of their upward stroke, strike against an arcuate ridge or projection forming a curved anvil 23 on the front of the segment 21 to cause a resilient action of the type-bars 14 against the 80 platen 16.

A guide 24 is provided to guide the type-bars 14 at the printing point, said guide being secured to the type-bar segment 21 by screws 25. 85

The outer portion 26 of the segment 21 having the radial slots 22 therein is raised from the body portion 27 of the segment to form an arcuate ridge or projection on the front of the segment, to provide sufficient 90 guiding surface in the slots 22 to guide the type-bars 14 towards the type-guide 24. It will also be seen that the type-bar anvil 23 is also raised from the body portion of the type-bar segment, and that it is in the form 95 of an arc so as to be the same distance away from the pivot of each type-bar.

A cross-bar or bridge 28 (Figure 3) is placed against the front face of the body portion 27 of the type-bar segment 21, said 100 cross-bar 28 being provided with an arcuate portion 30 fitting into an arcuate groove 31 formed between the spaced type-bar anvil 23 and the projecting outer part 26 of the type-bar segment 21. 105

The segment may be readily located relatively to the cross-bar 28, to bring rivet holes 32 and 33 into register with each other, by

opposing portions including the anvil 23 and the ends 34 of the outer portion 26, between which the cross-bar 28 is placed. The type-bar segment 21 may then be rigidly secured to the cross-bar 28 by rivets 35, which may be headed in the back of the segment (Figure 4) after assembling.

After the segment 21 and cross-bar 28 are assembled the latter may be secured in place 10 on a main frame 36 of the machine. For this purpose, the cross-bar 28 has two lateral extensions 37 to rest on ledges 38 projecting inwardly from the main frame 36 upon which it is held in place by suitable 15 screws 40.

In this construction, it will be seen the cross-bar 28 reaches from one side of the machine to the other and is located in front of the segment 21, without interfering with 20 the type-bar guide 24 or obstructing the type-bar anvil.

The arcuate portion 30 of the cross-bar 28 is L shaped in cross-section, the horizontal forward extension or flange 41 of 25 the L being located near the slots 22, in which the type-bars move.

Thus, the extension 41 serves as a protector or guard to keep the detritus, resulting from erasures against the platen, 30 from falling into said slots; for ordinarily foreign matter of various kinds collects on the grooved portion 31 and eventually overruns the edge and clogs the slots. It will be seen that the arcuate portion of the cross-bar is curved at 42, providing a forwardly 35 inclined surface, to prevent such accumulation on the extension 41. So long as foreign matter cannot accumulate and pile up on the forwardly-inclined surface 42 of the ledge or flange 41, it cannot fall off this ledge in a quantity large enough at any one time to clog the guide-slots 22.

One of the advantages in making the cross-bar and segment of two separate pieces is to avoid interference of the lateral projections 37 with the various tools used to machine the segment.

It will be noted that the arcuate portion 30 of the cross-bar 28, and the arcuate portion 23 of the segment 21, together with the arcuate slotted ridge 26 of the latter, co-operate to form interengaging parts which interlock to position the segment 21 against both lateral and vertical sliding movement on the cross-bar 28. It will be further noted that the arcuate portion 30 of the cross-bar, which fits into the groove 31 of the segment, is thereby countersunk into the front face of the segment to an extent so that its front 60 faces are flush, respectively, with the front face of the anvil 23 and of the slotted ridge 26, the ridge 26 being of greater height or projecting farther than the anvil 23 to an extent corresponding to the width of the 65 forward extension or flange 41 on the arcu-

ate portion 30 of the cross-bar, as is clearly shown in Figures 1 and 2 of the drawings. It will be evident, by reason of this arrangement, when the rivets 35 are in place, that a very firm and compact construction is produced.

Variations may be resorted to within the scope of the invention, and portions of the improvements may be used without others.

Having thus described my invention, I 75 claim:

1. In a typewriting machine, the combination with radially arranged type-bars to print at a common point against a platen, of a segment to support said type-bars, a 80 curved anvil on said segment against which the type-bars may strike, and a cross-bar arranged at the front of said segment to support the latter, said cross-bar having an arcuate portion to fit under said anvil. 85

2. In a typewriting machine, the combination with radially arranged type-bars to print at a common point against a platen, of a segment to support said type-bars, said segment having an arcuate groove therein, 90 and a cross-bar to support said segment, said cross-bar having an arcuate portion to fit into the groove.

3. In a front-strike typewriting machine having a platen and radially-arranged type-bars to print at a common point against the front of the platen, the combination of a segment for pivotally supporting the type-bars, a segment-supporting cross-bar at the front of the segment and having a middle 100 portion below the top of the segment so that the middle portion of the segment extends upwardly above the middle portion of the cross-bar, and a type-bar guide secured to the front of the segment above said middle 105 portion of the cross-bar.

4. In a front-strike typewriting machine having a platen and radially-arranged type-bars to print at a common point against the front of the platen, the combination 110 of a segment for pivotally supporting the type-bars and having spaced projections on one face thereof, and a segment-supporting cross-bar extending across the face of the segment between said projections, said projections being so arranged and the cross-bar being so shaped as to position the segment on the cross-bar against both lateral and vertical sliding movement thereon. 115

5. In a front-strike typewriting machine 120 having a platen and radially-arranged type-bars to print at a common point against the front of the platen, the combination of a segment for pivotally supporting the type-bars, an arcuate ridge or projection on the 125 front of the segment having slots therein for guiding the type-bars and forming an arcuate upper shoulder, and a segment-supporting cross-bar extending across the front face of the segment and having an arcuate 130

portion overlying said arcuate upper shoulder, said arcuate portion of the cross-bar having a forwardly inclined upper surface to shed foreign matter so as to prevent its 5 accumulation thereon.

6. In a front-strike typewriting machine having a platen and radially-arranged type-bars to print at a common point against the front of the platen, the combination of a 10 segment for pivotally supporting the type-bars, and a segment-supporting cross-bar countersunk into one face of the segment so as to be substantially flush therewith.

7. In a front-strike typewriting machine 15 having a platen and radially-arranged type-bars to print at a common point against the front of the platen, the combination of a segment for pivotally supporting the type-bars and having spaced projections on one 20 face thereof, and a segment-supporting cross-bar on the machine extending across the face of the segment between said projections and having outer faces substantially flush with the outer faces of said projections.

8. In a typewriting machine, the combination with radially-arranged type-bars to print at a common point against a platen, of a segment to support said type-bars, said 30 segment having an arcuate groove therein, and a cross-bar on said machine to support said segment, said cross-bar having an arcuate portion to fit into the groove, the cross-bar being flush with the front faces of the 35 segment.

9. In a front-strike typewriting machine having a platen and radially-arranged type-bars to print at a common point against the front of the platen, the combination of a 40 segment for pivotally supporting the type-bars, an arcuate ridge or projection on the front of the segment having slots therein for guiding the type-bars and forming an arcuate upper shoulder, and a cross-bar on 45 the machine secured to the segment at the front thereof to support the latter and having an arcuate portion to fit over said arcuate upper shoulder.

10. In a front-strike typewriting machine 50 having a platen and radially-arranged type-bars to print at a common point against the front of the platen, the combination of a segment for pivotally supporting the type-bars, an arcuate ridge or projection on the 55 front of the segment having slots therein for guiding the type-bars and forming an arcuate upper shoulder, a cross-bar on the machine secured to the segment at the front thereof to support the latter and having an 60 arcuate portion to fit over said arcuate up-

per shoulder, and a type-bar guide secured to the front of the segment above the arcuate portion of the cross-bar.

11. In a front-strike typewriting machine having a platen and radially-arranged type-bars to print at a common point against the front of the platen, the combination of a segment for pivotally supporting the type-bars, an arcuate ridge on the front of the segment having slots therein for guiding 65 the type-bars, a second arcuate ridge above the first forming an anvil for the type-bars to strike against, an arcuate groove being formed between the two said ridges, and a segment-supporting cross-bar on the machine having an arcuate portion to fit into the groove between the ridges.

12. In a front-strike typewriting machine having a platen and radially-arranged type-bars to print at a common point against the 80 front of the platen, the combination of a segment for pivotally supporting the type-bars, an arcuate ridge on the front of the segment having slots therein for guiding the type-bars, a second arcuate ridge above 85 the first forming an anvil for the type-bars to strike against, an arcuate groove being formed between the said two ridges, a segment-supporting cross-bar on the machine having an arcuate portion to fit into the 90 groove, and a type-bar guide secured to the front of the segment above the anvil-forming ridge.

13. In a front-strike typewriting machine 95 having a platen and radially-arranged type-bars to print at a common point against the front of the platen, the combination of a segment for pivotally supporting the type-bars, the segment having an arcuate groove in the front side thereof and having radial 100 slots below the groove for guiding the type-bars, and a segment-supporting cross-bar at the front of the segment having an arcuate portion to fit into the groove.

14. In a front-strike typewriting machine 105 having a platen and radially-arranged type-bars to print at a common point against the front of the platen, the combination of a segment for pivotally supporting the type-bars, and a segment-supporting cross-bar 110 extending across one face of the segment, the segment and the cross-bar having inter-engaging parts to interlock to position the segment on the cross-bar against both lateral and vertical sliding movement thereon.

ALFRED G. F. KUROWSKI.
